REEL AND HOLDER FOR DRAIN CLEANER
SNAKES

Frank L. Carson, Hollywood, Calif.

Application May 1, 1946, Serial No. 666,333

4 Claims. (Cl. 15—104.3)

1

This invention relates to improvements in apparatus for use in cleaning drains or waste pipes and more particularly to apparatus of the character commonly referred to as "plumber's snakes or cleaning wires."

It is a primary object of the present invention to provide improved construction of a cleaner of the type usually known as a top snake or can snake and which is constructed so that it may be quickly and efficiently operated by one man and compactly stored when not in use.

More particularly, it is an object of the invention to provide a novel construction of holder for the flexible snake into which or from which the snake can be readily reeled and which will efficiently function to prevent the coil thereof from becoming tangled within the holder.

Still another object of the invention is to provide a holder having novel means for restraining the snake against being withdrawn therefrom and which may be utilized for regulating the paying out of the snake or the drawing in thereof to effectively prevent tangling.

Still another aim of the invention is to provide a holder having an internally disposed handle arranged to suspend the weight of the holder and snake in a balanced position around the hand.

Still a further object of the invention is to provide a device possessing the above described features which is of extremely simple construction capable of being economically manufactured and sold and which is durable and will function efficiently for its intended purposes.

Other objects and advantages of the invention will hereinafter become more fully apparent from the following description of the drawings, which illustrate a preferred embodiment thereof, and wherein—

Figure 1 is a top plan view of the improved drain cleaner;

Figure 2 is an enlarged longitudinal sectional view thereof taken substantially along a plane as indicated by the line 2—2 of Figure 1, and

Figure 3 is a fragmentary transverse sectional view of the drain cleaner, taken substantially along a plane as indicated by the line 3—3 of Figure 2.

Referring more specifically to the drawings, the drain cleaner in its entirety is designated generally 5 and includes an elongated flexible member 6, commonly referred to in the trade as a "plumber's snake or cleaning wire." The snake or cleaning wire 6 may be in the form of a flexible cable, but as disclosed, is preferably

embodied in the form of a closely coiled wire having an enlargement or head 7 at its outer or forward end. The snake 6 is preferably embodied in the form, as disclosed, in order to produce a structure which will be sufficiently flexible to pass around curves or elbows in a drain without being obstructed thereby, but yet which is sufficiently resilient to normally extend in substantially a straight line and be sufficiently rigid to dislodge obstructions that may be encountered in a drain pipe.

The snake 6 is mounted in a reel or holder, designated generally 8, which is substantially cone or funnel shaped and which includes an outer section 9 and an inner section 10. The outer section 9 is provided with a restricted forward end, designated generally 11 including a restricted neck 12, having an internal diameter slightly greater than the diameter of the snake 6, and a flared mouth 13, disposed beyond the neck 12, forming the open forward end of the holder or reel 8. Inwardly from the inner end of the neck 12, the outer section 9 includes a substantially uniformly flared annular portion 14 which terminates at its enlarged end in an annular portion 15 which is of substantially uniform diameter and which terminates in an in-turned annular edge portion 16.

The inner section 10 includes an inner end 17 which is substantially flat and disposed transversely to the axis of the holder 8 and from which projects an annular, rearwardly extending and substantially uniformly flared portion 18 which is disposed within and substantially concentric to the flared portion 14. The portion 18 at its rear end merges with an annular portion 19 which is disposed substantially concentric to the portion 15 and which terminates in an outturned annular edge 20 which is partially overlapped by the inturned edge 16.

From consideration of Figure 2, it will be readily apparent that the inner and outer holder sections 10 and 9, respectively, are disposed substantially concentric from a point in transverse alignment with the end 17 to the rear end of the holder 8, and said concentric portions are spaced apart a distance slightly greater than the diameter of the snake 6 to form a substantially conical receiver or chamber 21 for housing the snake. The sections 9 and 10 are relatively rotatable to thus provide a reel or holder formed of swivelly connected sections.

A hollow handle 22 is provided with a head 23 having an outer portion which is shaped and sized to abut flush against the outer side

of the end 17 and the adjacent part of the portion 18. The head 23 may be secured to the portions 17 and 18 in any suitable manner as by welding, or may be formed integral therewith. The head 23 is provided with an axially disposed and internally threaded bore 24, the outer end of which registers with an opening 25 in the end 17, and the inner end of which opens into the hollow interior 26 of the handle 22.

An elongated thumb screw 27 has a shank provided with a threaded portion 28, adjacent its shank end, which threadedly engages the bore 24 and which extends therethrough and through the opening 25. Beyond the threaded portion 28, the shank of the thumb screw 27 terminates in a tapered end 29 with a pitch which is substantially concentric to the casing portion 14, for a purpose which will hereinafter become apparent. The opposite end of the shank of the thumb screw 27 extends loosely through the handle recess 26 and terminates at its rear end in a knob 30 which is disposed behind the handle 22.

As best illustrated in Figures 2 and 3, the snake 6 is normally housed in the conical annular chamber 21 being coiled therein with the convolutions thereof disposed in abutting engagement. The inner end of the snake 6, not shown, is disposed against the overlapping portions 16 and 20 and is suitably secured to the inner holder section 10.

To pay out the snake 6 for feeding it into an obstructed drain or the like, not shown, the thumb screw 27 is positioned, as shown in Figure 2, and the handle 22 is grasped by one hand of the operator and the free hand engages the outer holder section 9, for example around the neck 12 thereof. The first mentioned hand is then used to revolve the section 10 with respect to the section 9 in a direction, opposite to the direction that the section 10 would turn to reel in the snake 6, for example in a clockwise direction, as illustrated in the drawings. This will cause the snake 6 to be paid out through the neck 12 and the flared mouth 13, so long as the inner section 10 is revolved relatively to the outer section 9, which is held stationary by the hand of the operator for supporting the drain cleaner 5. When the snake 6 has been paid out to the desired length, as when an obstruction is encountered, the thumb screw 30 may be turned to advance the shank thereof to cause the end 29 to be moved into clamping engagement with a portion of the snake which is disposed between the end 29 and the adjacent portion of the outer section 9. With the snake thus clamped in the holder 8, said holder can be actuated manually to work the snake head 7 past the obstruction without danger of a part of the snake being pushed back into the receiver 21 and become entangled therein. By similarly holding and revolving the casing section 9 in the opposite or counter-clockwise direction, the snake 6 will be reeled in through the neck 12 and closely coiled into the receiver 21 to resume the position as shown in Figure 2. The thumb screw 27 can then be advanced for clamping the snake in its position of Figure 2 to hold the snake in a retracted position, while not in use. The thumb screw 27 may also be utilized through proper adjustment for retarding the reeling in or the reeling out of the snake 6 to avoid tangling thereof.

From the foregoing it will be readily apparent that the holder 8 provides a construction wherein the handle 22 is disposed within the holder, so that the holder and the coiled snake will be dis-

posed in a balanced position around the hand grasping the handle 22 and so that the support of the drain cleaner 5 will be substantially in alignment with the direction in which the snake is reeled in or out from the holder 8 thereof to facilitate the efficient operation of the apparatus with the least manual effort on the part of the operator.

Various modifications are contemplated and may obviously be resorted to without departing from the spirit and scope of the invention as hereinafter defined by the appended claims.

I claim as my invention:

1. In a drain cleaner, a holder or reel formed of inner and outer swivelly connected sections, said sections combining to form an annular, substantially funnel shaped chamber having a restricted outlet at one end of the holder and being closed at its opposite end, an elongated flexible member normally nested in coiled relationship in said annular chamber and having one end projecting through the restricted outlet of the holder, and means for manually supporting the drain cleaner and retaining the outer holder section in a stationary position while the inner section of the holder is revolved for reeling in or paying out said flexible member.

2. In a drain cleaner, a holder or reel formed of inner and outer swivelly connected sections, said sections combining to form an annular, partially cylindrical and partially conical shaped chamber having a restricted outlet at one end of the holder and being closed at its opposite end, an elongated flexible member normally nested in coiled relationship in said annular chamber and having one end projecting through the restricted outlet of the holder, said outer holder section being adapted to be manually engaged and held stationary, and a handle adapted to be manually engaged for revolving the inner holder section relatively to the outer holder section for reeling in or paying out said flexible member, said handle being fixedly disposed relatively to said inner holder section and arranged axially thereof.

3. In a drain cleaner, a holder or reel formed of inner and outer swivelly connected sections, said sections combining to form an annular, substantially funnel shaped chamber having a restricted outlet at one end of the holder, an elongated flexible member normally nested in coiled relationship in said annular chamber and having one end projecting through the restricted outlet of the holder, said outer holder section being adapted to be manually grasped for supporting the drain cleaner and for maintaining said outer section in a stationary position while the inner section of the holder is revolved for reeling in or paying out said flexible member, a handle fixedly disposed relatively to said inner holder section and arranged axially thereof and adapted to be manually grasped for revolving the inner holder section relatively to the outer holder section, and an elongated thumb screw adjustably mounted in the holder for movement axially thereof, said thumb screw having a portion extending into said annular chamber, adjacent the restricted neck, for engagement with the flexible member.

4. A drain cleaner comprising a substantially cone shaped reel provided with an annular substantially conical chamber, said reel chamber having a restricted outlet at one end thereof and being defined by swivelly connected inner and outer reel sections; and an elongated relatively flexible member normally nested in coiled relationship in said annular chamber and having one

end projecting through said restricted outlet, said flexible member being adapted to be reeled in or out with respect to the reel by the rotation of one of said sections with respect to the other section, a handle rigidly secured to the inner section and disposed within and axially of the reel, and an elongated thumb screw disposed longitudinally of the handle and in threaded engagement therewith, said thumb screw having an end extending into the reel chamber and adjustably disposed with respect thereto for regulating the movement of the flexible member relatively to the holder.

FRANK L. CARSON.
